AUTOMATIC DUMP SKIP

Clifford D. Woodward and Francis E. Ralph,
Butte, Mont., assignors to Anaconda Copper
Mining Company, a corporation of Montana

Application October 10, 1944, Serial No. 557,981

3 Claims. (Cl. 214—117)

1

This invention relates to mine skips, particularly of the type which are vertically suspended on cables or the like and which usually are used in upright shafts to raise or lower loads of materials, and has for its object the provision of an improved bottom dump skip. The invention provides an improved skip having an automatically opened and closed door near its bottom through which the material in the skip is discharged.

In one of its advantageous embodiments, the invention provides a door in the side of the skip near the bottom which is automatically raised to dump the skip as the skip moves to its dumping position, and means for closing the door. In a preferred arrangement of apparatus, the door is raised or slid upwardly by means on the skip which engages an actuating member located at the place where the skip is dumped and the door is raised to its open position while the skip is moving to its dumping position. Advantageously, the means on the skip comprise a lever-actuated suspension means including a cable or chain passing over a roller or pulley, one end of which engages the lever and the other the door, and the actuating member may be a cam or profile guide securely attached to the surrounding fixed structures at the dumping station which operatively engages the lever to open the door. The actuating member may be provided with means for moving it into or out of operative position to permit the skip to move past dumping stations without dumping when desired. In order to facilitate the smooth operation of the door, a separate mechanism comprising the trunnion roller, lever, cable, pulley and actuating mechanism are provided at both upright side edges of the door.

An especially suitable skip according to the invention is in the form of an oblong rectangular box being relatively deep in its upright direction and has an inclined bottom with the door on the side opposite the inclined bottom. The door is most effectively located at the bottom of an upright side to facilitate its raising and lowering and the inclined bottom being opposite directs the material to the door, thereby facilitating the dumping and minimizing the amount of material retained in the skip. In other words, the skip lumps clean and in a very short time.

The invention also includes improved means for securing the cables to the opposite sides of

2

the skip door in such manner as to facilitate equalizing tensions placed on them.

These and other novel features of the invention will be better understood after considering the following discussion taken in conjunction with the accompanying drawings, in which:

Figs. 1, 2 and 3 are side elevational views of skip apparatus of the invention in three different positions;

Fig. 4 is a side elevational view of the lower portion of a skip illustrating another embodiment of the invention;

Fig. 5 is a front elevational view of the skip of Fig. 4;

Figs. 6 and 7 are fragmentary side and front elevational views of still another embodiment of the invention;

Fig. 8 is an enlarged view of a detail of the invention; and

Figs. 9 and 10 are fragmentary vertical and horizontal sectional views, respectively, through the adjustment bracket for the cables shown in Figs. 6 and 7.

The apparatus of the invention, illustrated more or less diagrammatically in Figs. 1, 2 and 3, comprises a skip 1 which is of relatively small rectangular cross-sectional area and relatively long with a downwardly sloping bottom 2. The skip is supported in a vertical position on the cable 3 which is attached to a bail 4 connected to the upper side walls of the skip by means of the trunnions 5. The skip is guided in its upward and downward travel in the mine shaft by the lower guide 6 and the upper guide 7 which engage the guide rails 8 in the form of timbers or the like. It is understood that similar guiding means are mounted on the opposite side of the skip.

The skip door 9 is in the form of a flat plate which may be raised and lowered through suitable securing guides by means of the cable or chain 10. The door is preferably located opposite the inclined bottom 2 so that when the door is opened the material will slide through the opening without leaving any appreciable residue. The cable 10 passes around the roller or pulley 11 and is secured to the upper end of the lever 12 which is pivotally connected to the skip at its opposite end by the pin 13. At a position near the pivoted end of the lever, a trunnion roller 14 is connected by an extension bracket 15. At a position above

the place where the door opens to dump the skip, a cam or profile member 16 in the form of a rigid metal plate is secured to the surrounding permanent structure, such as the timbering of the shaft. As the skip moves in its upward or downward direction, the trunnion roller 14 engages the cam member 16, swinging the lever in a counterclockwise direction, as best shown in Fig. 2, to cause the chain 10 to pull the door to its open upward position. The material to be dumped slides through the open side, and as the skip moves either above or below the position shown in Fig. 1, the door falls to its closed position, carrying the lever 12 to the position shown in Figs. 1 and 3.

It is frequently necessary, and especially in the underground workings, to move the skip upward or downward past dumping stations without opening the door. To this end, the invention provides a cam member which is adjustably mounted on the surrounding permanent structure. As illustrated in Figs. 1, 2 and 3, the cam member is pivotally connected at the top on the pin 17 and is attached to a bracket 18 at the bottom. In operating the skip without opening the door, the profile member is disengaged from the bracket 18 and swung to the right, as shown in Fig. 3, where it is completely out of engagement with the trunnion roller 14. Any time it is desired to open the door to dump material at the place where the cam member is located, the cam member is swung to the position shown in Figs. 1 and 2.

The apparatus illustrated in Figs. 4 and 5 comprises a skip 20 which has a double side wall 21, double inclined bottom 22 with a space therebetween filled with a shock-absorbing material, such as wood or rubber 23. The lower guide 24 is in the form of a U-shaped channel and slides over the guide rail 25. The door 26 has a plurality of angle bars 27 attached thereto, as by welding, to reinforce the door. Blocks 28 and 29 are formed of individual pieces of bar steel securely fastened to the angle bars 30 which form the side guides for the door. Blocks 28 are both welded and bolted to the guides 30, while blocks 29 are merely bolted to guides 30 and are accordingly easily removable. Blocks 29 serve as bumpers, so that when the door 26 drops into position by gravity, the shock is absorbed thereby and transmitted to guide bars 30, preventing the bottom of the door from striking on the discharge lip of the skip. To transmit this blow from the falling door 26 to bumper blocks 29, there is a heavy metal bar 29' welded to the top of the door which extends over blocks 29 and to which is attached the adjustable bracket for the chain or cable 32. The side edges of the door slide inside the angle bars 30 and in the recesses 31.

As best shown in Fig. 5, the door is suspended on two cables 32 which pass upwardly and over the pulleys 33 attached to the sides of the skip. Each of the cables is attached at its upper end to a lever 34 which is pivotally connected to a side of the skip by a bolt 35. The trunnion rollers 33 are connected to the levers 34 by the brackets 37. As shown in Fig. 4 the cam member 38 is formed of a flat plate with a reinforcing rib on the back surface insuring the desired stiffness. The profile of the cam member 38 over its entire length is the same as shown for the cam member 16 of Figs. 1 to 3. In order to prevent the door being carried upwardly beyond the desired position, the stop member 40 in the form of a bar is connected across the front of the skip.

The modified form of skip illustrated in Figs. 6 and 7 comprises an angle bar 45 secured along

each side wall of the skip, at the front thereof, to which at spaced intervals, door-engaging fingers 46 are attached as by welding (see Fig. 8). These fingers are provided with a groove 47 in which the side edges of the door slide, and while the door is accordingly prevented from being forced either inward or outward, it is free to move upward or downward with a minimum of jamming. The heavy bar 48 extending across the door and forming a part thereof has a bracket 49 attached to each end thereof comprising a wedge-shaped, adjustable member 50 to which the chain or cable 51 is attached and a cooperating wedge-shaped block 52 having an inclined face with the same slope as the inclined face of the member 50. Member 50 has elongated slots 53 and 54 permitting it to be slidably mounted over the bolts 55 and 56. The adjustable member 50 may be adjusted up or down to maintain an equal tension for both cables or chains merely by loosening the bolts 55 and 56 to set the member 50 in the position desired. As shown in Figs. 9 and 10, the bar 48 is thickened at the end where the wedge portions 50 and 52 are secured to it, and is rabbeted or otherwise formed at its back with a space 57 which receives the door-engaging fingers 46 as the door moves up and down past them.

The improved apparatus of the invention eliminates the necessity for inverting the skip during dumping, as has been the practice heretofore, and may be used in confined places in underground workings without requiring a great deal of space. The door operating in combination with the inclined bottom provides a skip which discharges its entire load. It may, accordingly, be used very effectively even in freezing weather for hauling moist material without an appreciable accumulation of residue in the skip. One important feature of the invention is the free return of the door to its closed position merely by gravity. There is, accordingly, no operating mechanism likely to become injured should the door become jammed in its open position. If the door of the invention becomes jammed when open, the skip may, nevertheless, travel in its normal manner as the door may later be closed after removing the obstruction. One of the features of the invention which tends to eliminate the sticking of the door is the slotted guides in the form of a series of fingers through which the edges of the door slide.

We claim:

1. In a skip assembly of the character described, in which the skip is arranged for travel to and from a dumping station and comprises side walls and a bottom with a vertically slidable door in one side wall, means for opening the door at a dumping station comprising a lever pivotally mounted at one end on the skip, a pulley mounted on the skip above the door, a cable secured to the door and passing thence over the pulley to the free end of the lever, a cam follower mounted on the lever at a distance from its pivot, and a cam member mounted on a fixed structure adjacent the dumping station and adapted to engage the cam follower in such manner as to actuate the lever to pull on the cable and raise the door when the skip is brought to the dumping station.

2. In a skip assembly of the character described comprising side walls and a bottom, a vertically slidable door in one side wall, and a pair of cables secured one to each side of the door for lifting the door to the open position, the improved means for securing the cables to the door to facilitate equalizing the tension on the cables comprising

a bracket for attachment to each cable, said bracket comprising a first wedge block thicker at the bottom than at the top, means for attaching a lifting cable at the top of said first wedge block, a second wedge block thicker at the top than at the bottom overlying each first wedge block, and at least one bolt which when tightened clamps the first wedge block securely between the second wedge block and the door, said first wedge block having a vertically - elongated opening 10 through which said clamping bolt passes, so that when said bolt is loosened said first wedge block may be adjusted vertically relatively to the door and the second wedge block.

3. A skip assembly of the character described 15 comprising a skip adapted to travel to and from a dumping station and having side walls, a bottom and a door, means for opening the door at a dumping station comprising a depressible cam follower linked to the door to open the door when 20 the cam follower is depressed, and a cam member so mounted adjacent the dumping station that it may be moved, selectively, into an advanced position to engage the cam follower and depress it to cause the door to open when the skip is 25

brought to the dumping station and into a retracted position in which it does not engage the cam follower, so that when the cam is in such retracted position the skip may be brought to or past the dumping station without causing the door to open.
